(57) **CLAIM**

The ornamental design for an insect trap lid, as shown and described.

DESCRIPTION

FIG. 1 is a top perspective view of the insect trap lid;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The insect trap lid provides a supporting surface for an article placed on it, and provides a cover for a corresponding insect trap base placed below it.
